HOLD OPEN DEVICE

Benjamin S. Bernhard, Boston, Mass., assignor to
The American Hardware Corporation, New
Britain, Conn., a corporation of Connecticut

Application November 5, 1936, Serial No. 109,244

6 Claims. (Cl. 292—275)

My invention relates to a hold open device for doors.

It is the general object of my invention to provide an improved form of hold open device.

5 Another object is to provide a hold open device which is of relatively small size, of simple construction, and pleasing appearance.

It is another object to provide a hold open device in which the arms are at all times held 10 against pivotal end play.

It is another object to provide an improved form of hold open device providing for rolling frictional means for holding the hold open arms in hold open position.

15 Another object is to provide a hold open device the operative parts of which are enclosed to exclude foreign matter and which may operate in lubricant.

Other objects and various features of invention will be hereinafter pointed out or will become apparent to those skilled in the art.

In the drawing which shows, for illustrative purposes only, a preferred form of the invention—

25 Fig. 1 is a fragmentary top plan view of a door and casing, showing my improved hold open device applied thereto;

Fig. 2 is a fragmentary enlarged top plan view of the hold open device of Fig. 1, parts 30 being broken away to illustrate the interior construction, the hold open arms being shown in the hold open position;

Fig. 3 is a view similar to Fig. 2 but illustrating the arms in the door closed position;

35 Fig. 4 is a sectional view in a plane substantially through the axis of the pivotal connection between the hold open arms;

Fig. 5 is a top plan view of the parts shown in Fig. 4, the upper arm and nut being re-40 moved.

In said drawing, 5 indicates a door casing to which the door 6 is hinged. 7 indicates a well known or any desirable type of door closer and check. The arm 8 is non-rotatably connected 45 to the shaft of the door closer 7 in well known manner, while the longitudinally adjustable arm 9 is pivoted to the door casing. The arms 8—9 are pivotally connected to each other, all as is common practice.

50 In the preferred form shown the closer arm 8 is provided with a through bore or passage 10, an upper counterbore 11, and a lower counterbore 12. Within the passage 10 is a radially inwardly projecting or raised friction surface 13 55 which is preferably arcuate to provide an ex-

tended friction area. A member, which I term a cam member 14, extends into or through the through bore 10 and may be provided with a disk-like bearing portion 15 rotatably fitting within the counterbore 11. Within the counterbore 12 is a circular bearing plate 16 and the cam member 14 has an axially extending projection 17 preferably of angular cross section fitting within a corresponding aperture in the bearing plate 16 so that the bearing plate and cam member 14 rotate as a unit. Means such as a screw 18 serves to secure the cam member 14 and bearing plate 16 against separation. It will be noted that the disks or plates 15—16 serve as spaced apart bearings for the cam member and serve to hold the latter against all axial movement on the arm 8 and yet permit free rotation thereof.

The frame arm 9, or more properly the yoke 19 pivotally secured to the frame arm 9 at 20, 20 is provided on the under surface with radial serrations or teeth 21 and the upper surface of the cam member is provided with corresponding teeth 22 to interfit with the teeth 21 and thus assist in holding the cam member 14 and frame arm 9 in angularly adjusted position. In the preferred form the cam member has an upwardly extending pivot member 23 of circular cross section and the yoke 19 is provided with a circular aperture to fit over such pivot projection 23. A nut 24 screw threaded on the pivot 23 and engageable with the yoke 19 serves to force the yoke 19 into engagement with the cam member 14 when the cam member and yoke have been angularly moved to the desired 35 adjusted position.

The cam member 14 within the through bore 10 is provided with an eccentric 25 and there is provided a sleeve or ring 26 which is freely rotatable on the eccentric and also freely rotatable 40 within the bore 10. Now, when the arms 8—9 are moved relatively to each other, say, from the door closed position of Fig. 3 toward the door open position, the eccentric 25 turns in a clockwise direction and moves the ring bodily and 45 radially toward the surface 13 until some portion of said ring will engage said surface and block further turning movement. The area of contact is such that wear is very slight. Furthermore, since the ring is unrestrained, excepting when 50 wedged between the parts 25—13, it follows that different parts of said ring will engage the surface 13 on successive operations, thus distributing wear evenly entirely around the ring and greatly increasing the effective period of each 55

adjustment. Since the eccentric and ring are enclosed they may run in a suitable lubricant, if desired.

The adjustment of the device is relatively simple. The nut 24 is backed off to free the arm from the cam member 14. The door is then moved to the desired hold open position. By means of a screw driver the pivot projection 23, and consequently the entire cam member, is then rotated until the ring 26 forcibly engages the friction surface 13. The nut 24 is then turned down so as to clamp the arm 9 on the cam member 14 in the "hold open" position. Thereafter each time the door is swung to the "hold open" position, the ring 26 will frictionally engage said surface 13 and hold the door open as desired.

It will be seen that my improved hold open device is exceedingly simple in construction, of few parts, and cheap to manufacture. The device is small and of slight appearance. There are few parts to get out of order and it will be noted that there will be substantially no end play of the arms since the latter are not separated during the door closing movement of the arms but always remain in the same relative position axially of the pivotal connection.

While the invention has been described in considerable detail and a preferred form illustrated, it is to be understood that various changes may be made within the scope of the invention as defined in the appended claims.

I claim:

1. In a device of the character indicated, an arm having a through bore and counterbores at opposite sides thereof, an arm having a cam member with a bearing portion fitting in one of said counterbores and extending into said through bore, a bearing plate bearing in said other counterbore and secured to said cam member, whereby the latter is journaled on said arm on opposite sides thereof, said cam member having an eccentric portion engageable with a cam surface within said opening upon relative rotation between said arm and cam member.
2. In a device of the character indicated, an arm having a through bolt and counterbores at opposite sides of said arm, a cam member having a disk-like bearing portion fitting one counterbore and rotatable therein, said cam member having a part extending through said through bore, a bearing disk rotatably mounted in the opposite counterbore, means for non-rotatably securing said bearing disk to said cam member, whereby said cam member is rotatably secured to said arm by means of spaced apart bearings, said cam member having an eccentric portion within said through bore, a roller on said eccentric portion

and rotatable relatively thereto, said through bore having a cam surface engageable by said roller upon relative rotation of said arm and cam member, said cam member having an axially projecting pivot member, a second arm having an opening fitting said pivot member, said arm and cam member having mutually engageable interfitting serrations for adjustably holding said cam member and second arm in relative angular position, and a nut on said pivot member for forcing said second arm and said cam member into engagement with each other, whereby they are held against angular displacement, for the purpose described. 5 10 15

3. In a door hold open device, two pivotally connected parts, an eccentric carried by one part, a friction surface on the other part facing said eccentric, a friction ring between said surface and said eccentric and freely rotatable relatively to both said surface and said eccentric and 20 radially movable by the latter into frictional binding engagement between said parts, for the purpose described.

4. In a door hold open device, two pivotally connected parts, an eccentric carried by one part, a friction surface on the other part facing said eccentric, a friction ring between said surface and said eccentric and freely rotatable relatively to both said surface and said eccentric and radially movable by the latter into frictional binding 30 engagement between said parts, for the purpose described, with means to adjustably vary the angular starting position of the eccentric relatively to said friction surface.

5. In a door hold open device, two pivotally connected parts, an eccentric carried by one part, a friction surface on the other part facing said eccentric, a friction ring between said surface and said eccentric and freely rotatable relatively to both said surface and said eccentric and radially movable by the latter into frictional binding 40 engagement between said parts, for the purpose described, with means to adjustably vary the angular starting position of the eccentric relatively to said friction surface, said means being mounted 45 on said eccentric.

6. In a door stop, two pivotally connected parts, an eccentric carried by one part, a relatively raised arcuate portion on the other part forming a friction surface facing said eccentric and 50 spaced therefrom, a friction ring between said eccentric and said surface and freely rotatable relatively to both said shoulder and said eccentric and radially movable by the latter into frictional binding engagement between said eccentric and said surface, for the purpose described. 55

BENJAMIN S. BERNHARD.
